BEARING CONSTRUCTION FOR VACUUM CLEANER BRUSHES AND THE LIKE

Filed June 30, 1925

Inventor:
Henry T. Lang,
by *Henry T. Lang*,
His Attorney.

UNITED STATES PATENT OFFICE.

HENRY T. LANG, OF CLEVELAND, OHIO, ASSIGNOR TO ELECTRIC VACUUM CLEANER COMPANY, INC., OF CLEVELAND, OHIO, A CORPORATION OF NEW YORK.

BEARING CONSTRUCTION FOR VACUUM-CLEANER BRUSHES AND THE LIKE.

Application filed June 30, 1925. Serial No. 40,662.

This application is a continuation in part of my application, Serial No. 667,066, filed October 6, 1923.

In connection with vacuum cleaners having brushes in their nozzles which brushes are usually driven from the motor which drives the suction fan, trouble is often experienced due to dirt and grit getting into the bearings which may cause them to seize, thus damaging the bearing and causing annoyance to the user. Also, with such constructions trouble is sometimes experienced due to material wrapping around the brush shaft adjacent to the bearings and stalling the brush.

The primary object of the present invention is to provide an improved bearing construction for a vacuum cleaner brush or the like which is so constructed and arranged that dirt and grit cannot get into it and which on its outside presents a contour such that material is not likely to wrap around it and stall the brush. A further object of the invention is to provide a construction which after being initially lubricated will not again require lubrication for a very long time.

For a consideration of what I believe to be novel and my invention, attention is directed to the accompanying description and the claims appended thereto.

In the drawing, Figure 1 is a front view, partly in section, of a vacuum cleaner having a brush equipped with bearings embodying my invention; Fig. 2 is a sectional view on a larger scale of the improved bearing construction; Fig. 3 is a detail end view of the brush supporting means and Figs. 4, 5 and 6 are sectional detail views of modifications.

Referring to the drawing, 5 indicates a vacuum cleaner having a nozzle 6 in which is mounted a brush 7. The brush is supported at its ends by stub shafts 8 which are held in slots 9 in a disk 10 by means of spring fingers 11, the disks being suitably fixed to the end walls of nozzle 6 by screws 11a. It is driven by a belt 12 which runs on a pulley 13 on the brush and a pulley 14 on the end of shaft 15 of the motor which operates the fan of the vacuum cleaner. The construction so far described is a known one and is to be taken as typical of any suitable vacuum cleaner structure.

Referring now to particularly to Fig. 2, at each end of the brush cylinder 16, which in the present instance is shown as being con-

structed of wood, I provide a bearing stud 17 which has knurled or roughened end 18 and a shoulder 19. Stud 17 is formed integral with a socket 20 in which the end of cylinder 16 is fastened. Surrounding stud 17 is a bearing housing 21 provided with an outer end wall 22 in which stub shaft 8 is fastened. Wall 22 completely closes the outer end of housing 21. At the inner end of bearing housing 21 is a collar 23 provided with a forwardly projecting flange 24 over which is arranged a cup shaped end guard comprising a radial wall 25, an axially extending wall 25a and an inturned flange 25b. Walls 24 and 25a are concentric and stand in spaced relation to each other, providing between them an annular chamber. In this chamber is arranged a packing means 27 which packs against the adjacent surfaces of walls 24 and 25a. The packing means may be of any suitable character, it being shown in the present instance as comprising a felt washer. It is held in place by inturned wall 25a. This forms a dust guard which prevents dirt or grit working into housing 21. In housing 21 is a bearing 28 here shown as a ball bearing. Its outer race 29 fits tightly in housing 21 so it is held from turning and it is spaced from the end of the housing by a washer 30. The inner race 31 of the bearing

is fixed on the roughened end 18 of stud 17 and is positioned in spaced relation to collar 23 by shoulder 19. In the space between the inner end of the bearing and collar 23 is arranged an oil guard comprising an annular metallic housing 32 which opens toward stud 17. In housing 32 is a packing means 33 which packs against the outer surface of stud 17 at its inner end. Packing means 33 may be in the form of one or more felt washers.

The bearing housing 21, the ball bearing 28, the oil guard comprising housing 32 and packing 33, and the dust guard comprising the walls which form chamber 26 and packing 27 are assembled as a unit and form a complete unitary bearing structure which may be applied to a brush by forcing the outer end 18 of stud 17 into the opening of inner race 31. This serves to permanently attach the ball bearing structure to the brush, the two bearings at the end of the brush thus forming a permanent part of the brush structure. When the brush is assembled in the cleaner, stub shafts 8 are held from turning in slots 9 by the spring fingers 11 which

means that ball bearing housing 21 and the outer ball bearing race 29 are stationary. The inner ball bearing race 31 turns with the brush. When the ball bearing is assembled in housing 21, it is packed in lubricant and this lubricant is retained by the guard packing 33. A fairly heavy grade of grease is used and I have found that with this arrangement the original grease will last practically for the life of the cleaner. This is of great advantage in a household device such as a vacuum cleaner, for it means that the user does not have to bother with lubricating the brush bearings.

15 The packing 27 of the dust guard packs against the adjacent surfaces of walls 24 and 25^a and prevents any dirt or particles of grit finding their way into the bearing; and should any particles work past packing 27 even then they cannot reach the bearing without first passing radially inward between the end wall of socket 20 and the oil guard and thence past the oil guard packing 33. As a result the bearing is efficiently 20 protected from dust and grit.

25 The bearing housing and parts connected therewith are stationary, the brush cylinder 16 turning in them, and it will be noted that between the stationary and moving parts 30 there are no spaces or crevices within which material may become wound or embedded thereby stalling the brush.

35 As will be seen from Fig. 2, the dust guard comprising packing or sealing means 27 is located in radially-spaced relation to the adjacent walls of bearing housing 21 and brush cylinder 16, there being thus provided shoulders A and B, as is indicated in Fig. 2, which space the packing or sealing means 40 and its seams from the adjacent surfaces of the bearing housing 21 and cylinder 16. When picking up hair, string, or similar material, the tendency is always for it to wrap around the parts of smaller diameter, and in the present instance this will be the brush cylinder and the bearing housing. In doing this, however, by reason of the fact that the packing means 27 is spaced radially from these surfaces, the material will not 45 reach out to the packing seams between the relatively rotating parts and will not become wound up directly adjacent to them where it might cause binding. In other words, such material at most, will wind around 50 against shoulders A and B. The location of the packing means and the surfaces between which it is placed in radial spaced relation to the adjacent surfaces of the brush structure, therefore, is of material assistance in 55 preventing hair, string, thread and similar material from finding its way into the seams between the relatively moving parts.

60 In Fig. 4 I have shown an embodiment of my invention wherein the packing means 27, corresponding to packing means 27 of

Fig. 2, packs against the surface of socket 20^a, the packing means being held in an annular chamber formed by collar 23^a, forwardly projecting flange 24^a and the cup-shaped end guard 25^a.

70 In Fig. 5 is shown an arrangement similar to that shown in Fig. 4 except that there has been added thereto a thread guard 34 in the form of curved wall which extends partly over and encloses somewhat the packing 75 chamber. This guard protects the seam at C between the inner edge of the packing structure and the surface of the brush structure, preventing threads, hair, string or similar material from finding its way 80 into the seam.

85 In Fig. 6 is shown an arrangement similar to that shown in Fig. 4 except that a raised surface 35 is provided against which the packing rubs. This provides a shoulder 36 which corresponds to the shoulder B of Fig. 2, and serves to prevent hair and similar material from getting into the seam between the relatively rotating surfaces.

90 In accordance with the provisions of the patent statutes, I have described the principle of operation of my invention, together with structures which I now consider to represent the best embodiments thereof, but I desire to have it understood that the 95 structures shown are only illustrative and that the invention may be carried out by other means.

99 What I claim as new and desire to secure by Letters Patent of the United States, 100 is:

1. A bearing structure for vacuum cleaner brushes and the like, said structure comprising a housing having a closed end, a bearing comprising an inner race and an outer race mounted in the housing, a rotatable member having a stud on its end which stud is fastened to the inner race of the bearing, and packing means held in position by said housing which pack against said stud and against a surface of said rotatable member to prevent lubricant finding its way out of the bearing and foreign matter finding its way 105 into the bearing.

110 2. A bearing structure for vacuum cleaner brushes and the like, said structure comprising a housing having a closed end, a bearing comprising an inner race and an outer race mounted in the housing, a cylinder having a stud on its end which stud is fastened to the inner bearing race, packing means located between the end of said cylinder and the bearing to prevent lubricant leaking out of the bearing, and packing means located 115 between a surface of the housing and a surface which forms a part of said cylinder to prevent foreign matter from finding its way to the bearing.

120 3. A bearing structure for vacuum cleaner brushes and the like, said structures com- 125

prising a housing having a closed end, a bearing comprising an inner race and an outer race mounted in the housing, a cylinder having a stud on its end which stud is fastened to the inner bearing race, packing means located between the end of said cylinder and the bearing to prevent lubricant leaking out of the bearing, and packing means located between a surface of the hous-

ing and a surface which forms a part of 10 said cylinder to prevent foreign matter from finding its way to the bearing, said last-named packing means being located in radial spaced relation to the adjacent cylinder surfaces.

In witness whereof, I have hereunto set my hand this 26 day of June, 1925.

HENRY T. LANG.
